(57) CLAIM

The ornamental design for an aluminum beverage bottle, as shown and described.

DESCRIPTION

FIG. 1 is a perspective view of the claimed design for an aluminum beverage bottle;

FIG. 2 is a side view thereof;

FIG. 3 is a top view thereof; and,

FIG. 4 is a bottom view thereof.

The broken line showing in FIG. 4 is for environmental purposes only and forms no part of the claimed design.
